UNITED STATES PATENT OFFICE.

JOHN WOOD, OF NEW YORK, N. Y.

IMPROVEMENT IN CALISTHENIC PULLEYS AND SPRING-CORDS.

Specification forming part of Letters Patent No. 43,149, dated June 14, 1864.

To all whom it may concern:

Be it known that I, JOHN WOOD, of New York, N. Y., have invented an Improvement in Calisthenic Pulleys and Spring-Cords, of which the following is a specification.

My invention is designed to exercise the arms, &c., and is an arrangement of handles, suitable for the grasp of the hand, connected by a cord passing over a pulley or pulleys with an elastic spring or springs. The advantage of springs for this purpose over weights consists in the fact of their gradually-increasing resistance in proportion to their distension, so that the degree of exercise may be varied at will by simply pulling the handles to a greater or less distance.

Figures 1 and 2 represent, respectively, a front and side view of a board to which the pulleys, springs, &c., are attached.

It will be observed that two different arrangements of pulleys, &c., are shown in the

drawings, and other modifications will readily suggest themselves. The handles *a* and *a'* are fastened, by means of the cords *b* and *b'*, passing over the pulleys *c* and *c'*, to the springs *d* and *d'*, the handle *a'* being for the left hand, and the handle *a* for the right hand. A different arrangement is shown by the handles *e* and *e'*, attached to each end of the cord *f*, which hangs over the movable pulley *g*, suspended by the cord *h*, passing over the pulley *i*, and fastened to the spring *j*.

What I claim as my own invention, and desire to secure by Letters Patent, is—

The construction and arrangement of spring-cords, substantially as described, for calisthenic purposes.

JOHN WOOD.
